1

The present invention relates to wave transmission or signalling systems, more particularly to the transmission of speech signals, and has for its object to provide a novel method of and system for reducing the frequency range or band width required for the transmission of signals of this type.

For the transmission of speech signals, a transmission channel is generally required which passes the required speech frequencies with their relative amplitudes in order to enable a message to be understood clearly. For this purpose, a frequency band of about 300-3,000 cycles is required in practice. Various proposals have already been made to convert or modify the signals in such a manner that transmission is possible with a considerably smaller frequency range or band width of the transmission channel.

Thus, it has been proposed to transmit variable characteristic values or signals in place of the actual speech signals, these characteristic signals being representative of the fundamental frequency of the oscillations as well as the energy distribution of the various harmonics in the frequency spectrum, in such a manner that intelligible speech signals may be reconstructed at the receiving end by correspondingly controlled oscillating devices. Deviations from the fundamental frequency of the thus-obtained synthetic speech can, however, not be avoided in most cases and the variable energy distribution cannot be separately characterized for each speech component. This makes it impossible to avoid considerable changes from the original signals, with the result that it is difficult to understand the message and that the characteristic voice of the speaker is lost.

Other proposals relate to methods by means of which the frequency of the speech oscillations is reduced by subjecting the entire speech frequency spectrum to a frequency division process. It is found, however, that an oscillation process or complex signal wave containing several frequency components cannot be resolved in this way into a new signal wave of corresponding components being subdivided equally such as to one half their original frequency, from which the original process may again be obtained by frequency multiplication; for if an oscillation spectrum is subjected to a frequency division with known means, a new spectrum is obtained whose components have the same mutual spacing as in the original spectrum, so that no reduction in the band width can be achieved in this manner.

According to the present invention, the disad-

2

vantages of the previous methods of frequency division are overcome by subdividing the speech spectrum before transmission into several partial frequency ranges or sub-bands each of which contains not more than one vowel component of the speech being transmitted, and by, in turn, subjecting these components to a frequency division, whereby the signal to be transmitted will be reduced to a narrower band width. The original speech signals are again obtained at the receiver from the converted signal by individual frequency multiplication of the partial frequency ranges or sub-bands.

More specifically, the invention is based on the following considerations. Let it be assumed that an original speech signal voltage u is composed of two components having amplitudes a and frequencies W_1 and W_2 , respectively, the latter differing from each other by the fundamental frequency W , as is the case in a complex signal wave, such as a speech signal. Such a complex wave is expressed by the following equation:

$$\begin{aligned} u &= a \sin W_1 t + a \sin W_2 t \\ &= 2a \cos \frac{(W_1 - W_2)}{2} t \sin \frac{(W_1 + W_2)}{2} t \\ &= A \sin \frac{(W_1 + W_2)}{2} t \end{aligned} \quad (1)$$

Equation 1 represents an oscillation or wave having an average frequency

$$\frac{(W_1 + W_2)}{2}$$

and an amplitude A which varies at the rhythm of half the frequency difference $(W_1 - W_2)$; i. e.

$$A = 2a \cos \frac{(W_1 - W_2)}{2} t \quad (2)$$

By frequency division, there is obtained an alternating voltage v whose amplitude B , depending upon the frequency divider used, is either constant or corresponds to the amplitude A , while its frequency is reduced, such as by one half, to result in an output wave as follows:

$$v = B \sin \frac{(W_1 + W_2)}{4} t \quad (3)$$

With B being constant, this oscillation process or signal wave consists of a single component and it is possible to again obtain both original

components by frequency multiplication. If, however, B is equal to the original amplitude, then the following equation results:

$$v = 2a \cos \frac{(W_1 - W_2)}{2} t \sin \frac{(W_1 + W_2)}{4} t$$

$$= a \sin \left(\frac{3}{4} W_1 - \frac{1}{4} W_2 \right) t + a \sin \left(-\frac{1}{4} W_1 + \frac{3}{4} W_2 \right) t \quad (4)$$

This signal wave comprises two components whose frequency is about one half compared with those of the original components. The frequency difference between both components is, however, equal to the original value, i. e. $(W_1 - W_2)$, so that the band width required for transmission cannot be reduced by a frequency division of this type.

According to the improvements of the present invention, the original signal u is subdivided into components or frequency sub-bands and the frequencies of these components are then in turn divided into equal fractions substantially independently of each other. Thus, new components

$$a \sin \frac{Wt}{2}$$

are obtained from the original components $a \sin Wt$. By adding these components, a new corrected signal is obtained as follows:

$$v = a \sin \frac{W_1 t}{2} + a \sin \frac{W_2 t}{2} \quad (5)$$

In this case, the frequency difference of both components amounts only to

$$\frac{(W_1 - W_2)}{2}$$

i. e., one half the original band width, so that a channel with a correspondingly reduced pass-band characteristic may be used for the transmission.

In practice, the amplitudes a of the individual speech components are unequal and variable. These variations occur, however, more slowly than those of the fundamental frequency so that transmission means having a small band pass characteristic will be adequate for transmitting the amplitude changes. In order to transmit the varying amplitudes, it is possible, for instance, to cause the amplitudes of the corresponding frequency-divided components to vary in the same manner as the original components.

Normally, speech consists of more than two components. By subdivision into an adequate number of partial frequency ranges or sub-bands, the invention may be applied to a multiplicity of components without difficulty.

Speech signals, besides containing vowels with pronounced frequency components, also include consonants whose frequencies are more or less evenly distributed over the whole frequency spectrum. Experience has shown that a faithful transmission of these consonants is not necessary, that is to say, that an approximately correct characterization of the energy distribution over the individual partial bands is sufficient for practical purposes. This condition may be readily complied with by means of the arrangements according to the invention.

The invention both as to its objects and novel aspects will become more apparent from the following detailed description taken in reference to the accompanying drawings forming part of this specification, and wherein:

Figures 1 and 2 are basic block diagrams showing speech transmitting and receiving systems, respectively, embodying frequency division and multiplication means to reduce the signal band width in accordance with the principles of the invention.

Figures 3 and 4 are block diagrams showing transmitting systems according to the invention including means for transmitting the amplitude characteristics of the subdivided signal frequencies.

Figure 5 shows a transmitter according to the invention embodying modified means for amplitude transmission.

Figure 6 shows a receiver including one form of frequency multiplying means for restoring both the frequencies and amplitudes of the original signal waves.

Figure 7 illustrates a modification of Figure 6.

Figure 8 shows a further modification of a limited band width transmission system, utilizing separate pilot signals for transmitting amplitude characteristics.

Figure 9 and 10 illustrate systems according to the invention combined with speech scrambling arrangements for obtaining secrecy of transmission.

Figure 11 shows a more detailed circuit diagram of a system of the type shown in Figure 3.

Like reference characters identify like parts throughout the different views of the drawings.

In the arrangement shown in Figure 1, an original speech signal voltage u is divided into the sub-bands or partial frequency ranges $u_1, u_2 \dots u_n$ by means of band-pass filters (shown at EP₁ only for the first sub-channel). The first sub-channel may, for instance, cover the frequencies from 300-400 cycles and accordingly contains at the most one speech component, it being well known that even for a low male voice the fundamental frequency is above 100 cycles per second. By frequency division in a device TE₁, the corresponding partial signals $v_1, v_2 \dots v_n$ are obtained, the first of which may fall within the range between 150 and 200 cycles, assuming a division by one half. The total number of partial signals are then combined to produce the signal v to be transmitted and whose band width in the example shown has been halved compared with the original signal u . The band width may be still further reduced by reducing the frequencies $u_1, u_2 \dots u_n$ to one-third or smaller fractions.

In order to be able to utilize a favorable frequency range of the band-pass filters, the original signal before being filtered may be modulated with auxiliary frequencies so as to be shifted to a range falling within the passing range of the filter. After dividing the frequency sub-bands, a further frequency shift is generally necessary by modulation with corresponding auxiliary frequencies, depending on the particular type of transmission or signalling channel used.

At the receiving end, the received signal v is again subdivided by the filters BP₁ shown in Fig. 2, into the sub-bands $v_1, v_2 \dots v_n$. The original frequency sub-bands $u_1, u_2 \dots u_n$ are then obtained by correspondingly multiplying their frequency in the multiplier VE₁ and are then combined to reproduce the original signal wave u .

Since the amplitudes of the speech components are variable, it is necessary to transmit the amplitudes in addition to the varying frequencies. This is possible, for instance, by causing the amplitude of the frequency-divided components to be equal

to the amplitude of the original components. For this purpose, as shown in Fig. 3, an alternating voltage r_1 is obtained from component u_1 by first limiting its amplitude in AB. After dividing the frequency such as by one half in TE, there is obtained an alternating voltage s_1 having a constant amplitude and half the frequency

$$\frac{f_1}{2} = f_2$$

By forming the modulation product of signals s_1 and u_1 in the modulator M and suppressing the sum frequencies in the low-pass filter TP, a final oscillation v_1 results whose amplitude is proportional to the amplitude of signal u_1 and whose frequency is equal to one half the original signal frequency f_1 . If the frequency is divided in TE into

$$\frac{2f_1}{3} \text{ or } \frac{3f_1}{4}$$

of the original frequency, components having frequencies

$$\frac{f_1}{3} \text{ or } \frac{f_1}{4}$$

are obtained from the output of modulator M.

As is understood, arrangements similar to those shown and simply indicated by dash lines for the sake of simplicity in the drawing, are provided for each frequency sub-band, to result in a complete final signal v or u by combination of the individual signal components $v_1, v_2 \dots v_n$ or $u_1, u_2 \dots u_n$, respectively.

A modified arrangement according to the invention utilizing a so-called regenerative frequency divider is shown in Fig. 4. An alternating voltage t_1 having a fractional frequency such as

$$\frac{f_1}{2}$$

is obtained from the frequency-divided component v_1 after limiting in the limiter AB. By forming the modulation product of u_1 and t_1 in modulator M, there will again be obtained the component v_1 having a frequency

$$\frac{f_1}{2}$$

A frequency multiplier VE may be introduced between AB and M which, for instance, multiplies the frequency f_v of v_1 fourfold so that an alternating voltage s_1 with a frequency $4f_v$ results. By forming the modulation product in M, the difference frequency between voltages u_1 and s_1 is obtained as follows:

$$f_v = f_1 - f_s = f_1 - 4f_v \quad (6)$$

Accordingly,

$$f_s = \frac{f_1}{5}$$

Any other frequency ratio may be obtained with a different multiplication factor for VE. Thus, the arrangement according to Fig. 4 produces a frequency division by inverse or regenerative feedback and the use of a frequency multiplier (VE) for ratios greater than one half.

In the arrangement shown in Fig. 5, a control or pilot signal p_1 is obtained from each sub-band by rectifying in G and filtering in low-pass filter TP, respectively, this signal corresponding to the instantaneous amplitude of the respective sub-band. The divided partial signal s_1 of constant amplitude after passing through the limiter AB, is then controlled by p_1 in the modulator M so as

to obtain again a partial signal v_1 , the frequency of which is lower than that of signal u_1 and whose amplitude corresponds to the original amplitude of u_1 .

- 5 Dynamic compression may also be employed in connection with this type of amplitude control, if the control signal p_1 is given a corresponding amplitude relative to the signal u_1 by means of a suitable characteristic of the rectifier G.
- 10 Thus, for instance, p_1 may correspond to the root or logarithm of the amplitude of u_1 so as to be variable over a relatively small range, in which case the amplitude of v_1 varies over a range which is smaller than the amplitude range of u_1 . The main object of this arrangement is that, when u_1 has a small amplitude, there are already adequate amplitude values of v_1 , and when the amplitude of u_1 is large, the amplitude of v_1 increases only comparatively slightly. A corresponding dynamic compression with the arrangements shown in Figs. 1, 3 and 4 is, of course, also possible by the use of amplitude limiters with automatic amplification control in the individual sub-channels. Transmission means having non-linear transmission characteristics, such as amplifier tubes with curved operating characteristics, may also be used for limiting the amplitude. Existing harmonics may easily be suppressed by additional low-pass and band-pass filters, as they do not fall within the frequency range of the individual partial bands. Amplitude compression is also possible by controlling the amplitude of the subdivided frequency bands by means of non-linear rectification of the frequency bands to be divided or by means of a control voltage obtained from the undivided sub-bands by non-linear transmission. At the receiving end, the original amplitude differences may be restored again by corresponding dynamic expansion means inserted in the individual sub-channels.

- 40 A suitable receiving arrangement for use in connection with the transmitter according to Fig. 5 is shown in Fig. 6. The partial bands $v_1, v_2 \dots v_n$ are segregated from the received signal v by the band-pass filters BP. The frequencies may be multiplied by means of any known multiplying device. In the arrangement shown in the drawing, an auxiliary signal h_1 having a constant amplitude is obtained from v_1 by limiting its amplitude in AB and multiplying its frequency in VE, the frequency of h_1 , e. g., being equal to three times the frequency of v_1 . A modulation product of h_1 and v_1 comprising sum and difference frequencies is produced in the modulator M. The high-pass filter HP suppresses the difference frequencies so that an output partial signal u_1 is obtained having a frequency $f_u = 4f_v$. The frequency is thus multiplied fourfold, while the amplitude of u_1 corresponds to the amplitude of v_1 , thus obtaining the original signal frequency, as assumed. If dynamic compression is used at the transmitting end, corresponding dynamic expansion means will be required at the receiver.

- 45 A modified receiving arrangement is shown in Fig. 7. In the latter, the partial bands $v_1, v_2 \dots v_n$ obtained from the band filters BP, after passing through the amplitude limiter AB, are frequency multiplied in VE so that a signal h_1 is formed, the amplitude of which is constant, while its frequency is a whole number multiple of the frequency of v_1 . The amplitude of h_1 is controlled in the modulator M by a control signal q_1 . Control signal q_1 is obtained by rectifying a portion of signal v_1 in G and suppressing the higher fre-

quencies by means of low-pass filter TP; in other words, q_1 varies with the amplitude of v_1 and accordingly the amplitude of u_1 will be proportional to the amplitude of v_1 . If dynamic expansion is required due to a corresponding compression at the transmitter, this may be achieved in a simple manner by means of a corresponding non-linear characteristic of the rectifier G or an auxiliary non-linear transmission element in the path of the control voltage q_1 .

The frequency-divided signals may also be transmitted with constant amplitude, if supplementary characteristic signals are transmitted by special means, which signals are characteristic of the amplitude fluctuations. If the frequency-divided signals have a constant amplitude, the side bands due to the amplitude fluctuations disappear, so that a considerably narrower band width may be used; that is, the frequency of the individual sub-bands may be divided to larger fractions of the original frequencies. Such an arrangement is illustrated in Fig. 8. Similar to the arrangement shown in Fig. 5, a partial signal s_1 with constant amplitude is obtained by frequency division. Furthermore, a signal p_1 characteristic of the variable amplitude is obtained by rectification of a portion of u_1 in G and by low-pass filtering in TP. Since the frequency of p_1 is very low and not suitable for transmission, it is shifted by modulation in N, to produce a characteristic signal k_1 , the frequency of which falls within a range suitable for transmission together with the speech signals.

In order to obtain secret transmission, the partial signals or sub-bands may be interchanged or scrambled in a known manner before transmission according to a prescribed program so that only a person knowing the proper decoding key may obtain intelligible signals from the scrambled message. Such an arrangement is shown in Fig. 9. By modulation in the modulator M with an auxiliary frequency b_1 , the partial frequency band u_1 is at first shifted into a fixed or constant frequency range to which are also shifted all the remaining bands u_2 , u_3 , etc., by means of corresponding auxiliary frequencies and modulators. The passing frequencies of band-pass filters BP are thus the same for all partial channels. The partial frequency bands v_1 , v_2 , ..., v_n formed by subdividing the frequencies in TE are then scrambled by the permutator or scrambling device P. The scrambling process may be varied according to a definite plan in a manner well known in the art. After a further modulation in M' with the auxiliary frequency b_1 , the transposed bands are shifted back again by unequal amounts so that after the undesirable sum frequencies have been suppressed in the low-pass filter TP, there is obtained a final signal v suitable for transmission and having a frequency band width equal to the original signal u , but with the partial bands v_1 , v_2 , etc., mutually interchanged, in a manner well known in frequency substitution scrambling systems of this type.

The arrangement shown in Fig. 9, wherein the partial frequency bands are shifted into a common frequency range by means of modulator M, possesses the advantage that the filters BP and also the dividing devices TE may be designed for the same frequency range. Especially, the frequency division of the lowest speech frequency bands may cause difficulties which are avoided by the aforementioned frequency shift.

In arrangements utilizing characteristic signals

for the amplitudes as in Fig. 8, it is also possible to scramble both the partial signals in order to increase the secrecy, as is illustrated in Figure 10. In the latter, the permutator P serves to scramble all the sub-bands s_1 , s_2 , ..., s_n as well as the characteristic pilot signals k_1 , k_2 , ..., k_n . The interchanged characteristic values are again shifted into a frequency range suitable for transmission by a further modulation with suitable auxiliary frequencies d , while the interchanged sub-bands are shifted back by unequal amounts by means of a further modulation with suitable auxiliary frequencies e_1 .

Still greater secrecy may be achieved by an inversion of at least part of the various sub-bands by modulation with suitable auxiliary frequencies.

Figure 11 shows a more detailed constructional form of the arrangement illustrated in Figure 3. The amplitude limiter AB is shown to comprise two triodes V_1 , V_2 each of which has a limiting effect for negative input signals due to the lower bend in the characteristic curve. On account of the phase-reversing effect of V_1 , positive input signals of tube V_1 produce corresponding negative input signals for tube V_2 , so that the latter serves to limit positive input voltages and the former limits the negative input voltages. For dividing the frequency, a multi-vibrator with tubes V_3 , V_4 is shown in the drawing, the natural frequency of which has a whole number relationship with the average passing frequency of BP, so that the vibrator frequency is carried along or synchronized by the frequency of the sub-band u_1 and represents a whole fraction of the latter in a manner well known in frequency dividers of this type. A low-pass filter having a series inductance L and parallel condensers C is provided for suppressing the harmonics of the multi-vibrator oscillations. Modulator M is shown in the form of a push-pull circuit comprising tubes V_5 and V_6 . The sum frequencies resulting from the modulation are suppressed by the low-pass filter TP, while BP₁, BP₂, etc., are band-pass filters for subdividing the speech spectrum into frequency ranges.

The multi-vibrator shown in Figure 11 comprising tubes V_3 and V_4 is of the standard harmonic feedback type comprising a pair of resonant circuits in the anode circuits of the tubes. Resonant circuit R_1 from which is derived the divided output frequency is tuned to the desired fractional input frequency impressed upon the tube V_1 while the resonant circuit R_2 is tuned to the difference between the input frequency and the fractional frequency in a manner well known in the art. It is understood any other type of frequency divider circuit may be employed for the purposes of the invention.

When several messages are transmitted simultaneously, the frequency-divided partial signals of the various messages may be interchanged in order to obtain a high degree of secrecy. In this case, a special permutating device is used by which, for instance, the second partial signal of the first message is interchanged with the second partial signal of the third message according to a prescribed program, and so on. The separately transmitted characteristic amplitude values may, if necessary, also be scrambled in an analogous manner. If arrangements such as are shown in Figures 9 or 10 are used, it is also possible to interchange the third partial signal of the first message with the fifth partial signal of the second message, and so on, since the par-

tial signals before being interchanged are shifted into the same frequency range by modulating them with auxiliary frequencies *b*.

The arrangements according to the invention may also be employed for the recording of messages. When the messages are recorded on photograph records, the well-known needle noise which occurs in the higher speech frequency ranges is avoided, because the higher frequencies are no longer required for the recording.

For technical reasons it may be advantageous to divide the speech frequencies into partial frequency bands of different widths, that is, with the lower speech frequencies divided into narrower partial frequency ranges or sub-bands than the higher speech frequencies, so as to make sure that two components will not occur in a lower partial frequency channel.

When using the arrangements described above in multi-channel transmission systems, a suitable frequency shift may be employed to insure that the output signal *v* always falls within the desired transmission frequency range. With systems as shown in Figures 9 or 10, this is possible by a suitable choice of the demodulation or auxiliary frequencies *e*₁, *d*₁.

I claim:

1. A method of transmitting a complex signal wave comprising fundamental and harmonic frequency components, which consists in subdividing a signal wave to be transmitted into a plurality of frequency sub-bands each having a narrow width of an order so as to substantially include not more than one of said frequency components, equally dividing the frequency of each of said sub-bands, recombining and transmitting the divided-frequency sub-bands as a signal wave of reduced band width, again subdividing the received signal wave into its corresponding sub-bands, and equally multiplying the frequencies of said last-mentioned sub-bands and recombining the frequency-multiplied sub-bands to restore the original signal wave.

2. A method of transmitting speech signals which comprises subdividing a speech signal wave into a plurality of frequency sub-bands each having a narrow width of an order so as to substantially include not more than one vowel component, equally dividing the frequency of each sub-band, recombining and transmitting the divided-frequency sub-bands as a signal wave of reduced band width, again subdividing the received signal wave into its corresponding sub-bands, and equally frequency-multiplying said last-mentioned sub-bands and recombining the frequency-multiplied sub-bands to restore the original speech signals.

3. A method of transmitting speech signals which comprises subdividing a speech signal wave into a plurality of frequency sub-bands each having a width of an order of 100 cycles per second, equally dividing the frequency of each sub-band, recombining and transmitting the divided-frequency sub-bands as a signal wave of reduced band width, again subdividing the received signal wave into its corresponding sub-bands, and equally frequency-multiplying said last-mentioned sub-bands and recombining the frequency-multiplied sub-bands to restore the original speech signals.

4. In a system for transmitting a complex signal wave comprising fundamental and harmonic frequency components, means at the transmitter for subdividing a signal wave to be transmitted into a plurality of frequency sub-

bands each having a narrow width of an order so as to substantially include not more than one of said components, means for equally dividing the frequency of each sub-band, further means

5 for combining the divided-frequency sub-bands for transmission to a receiver as a signal wave of reduced band width, means at the receiver for again subdividing the received signal wave into its corresponding sub-bands, and further means
10 for equally multiplying the frequencies of the received sub-bands and recombining the frequency-multiplied sub-bands to restore the original signal wave.

5. In a speech signalling system, means at the transmitter for subdividing a speech signal wave to be transmitted into a plurality of frequency sub-bands each having a narrow width of an order so as to substantially include not more than one vowel component, means for equally dividing the frequency of each sub-band, further means
15 for combining the divided-frequency sub-bands for transmission to a receiver as a signal wave of reduced band width, means at the receiver for again subdividing the received signal wave into its corresponding sub-bands, and further means
20 for equally multiplying the frequencies of each received sub-band and recombining the frequency-multiplied sub-bands to restore the original speech signals.

30 6. In a speech signalling system, means at the transmitter for subdividing a speech signal wave to be transmitted into a plurality of frequency sub-bands each having a width of an order of 100 cycles per second, means for equally dividing the frequency of each sub-band, further means for combining the divided-frequency sub-bands for transmission to a receiver as a signal wave of reduced band width, means at the receiver for again subdividing the received signal wave into its corresponding sub-bands, and further means for equally multiplying the received sub-bands and recombining the frequency-multiplied sub-bands to restore the original speech signals.

35 7. In a system for transmitting speech signals, means at the transmitter for subdividing a speech signal wave to be transmitted into a plurality of original frequency sub-bands each having a narrow width of an order so as to substantially include not more than one vowel frequency, means for equally dividing the frequency of an amplitude-limited component of each sub-band and for combining the divided-frequency components with an unlimited component of the same sub-band to produce converted sub-bands of divided frequency and amplitude proportional to the amplitude of the respective original sub-bands, means for recombining and transmitting the converted sub-bands as a signal wave of limited band width, means at the receiver for again subdividing the received signal wave into its corresponding sub-bands, further means for equally frequency-multiplying amplitude-limited components of each received sub-band with unlimited components of the same sub-band to produce final sub-bands corresponding in both frequency and amplitude to said original sub-bands, and means for recombining said final sub-bands to restore the original signal wave.

70 8. In a system for transmitting speech signals, means at the transmitter for dividing a speech signal wave into a plurality of original frequency sub-bands each having a narrow width of an order so as to substantially include not more than one vowel frequency, means for equally dividing

11

the frequency of an amplitude-limited component of each sub-band to produce converted sub-bands of lower frequency, further means responsive to the amplitude of each sub-band to control the amplitude of the respective converted sub-bands, means for combining and transmitting the converted sub-bands as a signal wave of limited band width, further means at the receiver for again subdividing the received signal wave into its corresponding sub-bands, means for equally frequency-multiplying an amplitude-limited component of the received sub-bands to restore the original sub-band frequencies, further means responsive to the amplitude of each received sub-band for controlling the amplitude of the respective frequency-multiplied sub-bands to produce final sub-bands corresponding both in frequency and amplitude to said original sub-bands, and means for combining said final sub-bands to restore the original speech signals.

9. In a system for transmitting speech signals, means at the transmitter for subdividing a speech signal wave to be transmitted into a plurality of original frequency sub-bands each having a narrow width of an order so as to substantially include not more than one vowel frequency, means for equally dividing the frequency of an amplitude-limited component of each sub-band to produce sub-bands of lower frequency, modulating means for combining the divided-frequency sub-bands with non-limited components of the same sub-bands to produce converted sub-bands of lower frequency and amplitude proportional to the amplitude of the original sub-bands, means for combining and transmitting the converted sub-bands as a signal wave of limited band width, further means at the receiver for again subdividing a received signal wave into its corresponding sub-bands, means for frequency-multiplying amplitude-limited components of the received sub-bands to restore the original sub-band frequencies, further modulating means for combining the frequency-multiplied sub-bands with non-limited components of the respective sub-bands to produce final sub-bands corresponding in frequency and amplitude to said original sub-bands, and means for combining said final sub-bands to restore the original speech signals.

10. In a system for transmitting speech signals, means at the transmitter for subdividing a speech signal wave to be transmitted into a plurality of original frequency sub-bands each having a narrow width of an order so as to substantially include not more than one vowel frequency, means for equally dividing the frequency of amplitude-limited components of each sub-band to produce sub-bands of lower frequency, rectifying and filtering means to produce signals proportional to the amplitude of the original sub-bands, means for controlling the amplitude of the divided-frequency sub-bands by their respective control signals to produce converted sub-bands of lower frequency and amplitude proportional to the original sub-band amplitudes, means for combining and transmitting the converted sub-bands as a signal wave of limited band width, further means at the receiver for again subdividing the received signal wave into its corresponding sub-bands, means for equally frequency-multiplying amplitude-limited components of the received sub-bands to restore the original sub-band frequencies, means to restore the amplitude of the multiplied sub-bands to correspond with

12

the original sub-band amplitudes, and means for combining the resultant sub-bands to reconstruct the original speech signal.

11. The method of transmitting a complex signal wave comprising fundamental and harmonic frequency components which consists in subdividing a signal wave to be transmitted into a plurality of equal frequency sub-bands having a width of an order so as to substantially include not more than one of said frequency components, equally dividing the frequency of each of said sub-bands, recombining and transmitting the divided-frequency sub-bands as a signal wave of reduced band width, again subdividing the received signal wave into its corresponding sub-bands, and equally multiplying the frequencies of said last-mentioned sub-bands and recombining the frequency-multiplied sub-bands to restore the original signal wave.
12. The method of transmitting a complex signal wave comprising fundamental and harmonic frequency components, which consists in subdividing a signal wave to be transmitted into a plurality of frequency sub-bands of widths increasing from the lower toward the upper end of the frequency spectrum of said wave and being narrow enough so as to substantially include not more than one of said components, equally dividing the frequency of each of said sub-bands, recombining and transmitting the divided-frequency sub-bands as a signal wave of reduced band width, again subdividing the received signal wave into its corresponding sub-bands, and equally multiplying the frequencies of said last-mentioned sub-bands and recombining the frequency-multiplied sub-bands to restore the original signal wave.
13. In a signalling system for transmitting a complex signal wave comprising fundamental and harmonic frequency components, means at the transmitter for subdividing a signal wave to be transmitted into a plurality of frequency sub-bands of equal width being narrow enough so as to substantially include not more than one of said frequency components, means for equally dividing the frequency of all of said sub-bands, further means for combining the divided-frequency sub-bands for transmission to a receiver as a wave of reduced band width, means at the receiver for again subdividing the received signal wave into its corresponding sub-bands, and further means for equally multiplying the frequencies of the received sub-bands and combining the frequency-multiplied sub-bands to restore the original signal wave.
14. In a signalling system for transmitting a complex signal wave comprising fundamental and harmonic frequency components, means at the transmitter for subdividing a signal wave to be transmitted into a plurality of frequency sub-bands of unequal widths increasing from the lower to the upper end of the frequency spectrum of said wave and being narrow enough so as to substantially include not more than one of said frequency components, means for equally dividing the frequency of all of said sub-bands, further means for combining the divided sub-bands for transmission to a receiver as a wave of reduced band width, means at the receiver for again subdividing the received signal wave into its corresponding sub-bands, and further means for equally multiplying the frequencies of the received sub-bands and combining the frequency-multiplied sub-bands to restore the original signal wave.

15. In a system for transmitting a complex signal wave comprising fundamental and harmonic frequency components, means at the transmitter for subdividing a signal wave to be transmitted into a plurality of frequency sub-bands each having a narrow band width of an order so as to substantially include not more than one of said frequency components, means for equally dividing the frequency of amplitude-limited components of each of said sub-bands, means for restoring the amplitude variations of the divided-frequency sub-bands and combining the same into a signal wave of reduced band width for transmission to a receiver, means at the receiver for again subdividing the received signal wave into its corresponding sub-bands, further means for frequency-multiplying amplitude-limited components of the received sub-bands to restore their original frequencies, and means for restoring the amplitude variations of the frequency-multiplied sub-bands and combining the latter to reconstruct the original signal wave.

16. In a system for transmitting speech signals, means at the transmitter for subdividing a speech signal wave into a plurality of frequency sub-bands each having a band width of the order of 100 cycles per second, means for equally dividing the frequency of amplitude-limited components of each of said sub-bands, means for restoring the amplitude variations of the divided-frequency sub-bands and combining the same into a signal wave of reduced band width for transmission to a receiver, means at the receiver for again subdividing the received signal wave into its corresponding sub-bands, further means for equally frequency-multiplying amplitude-limited components of the received sub-bands to restore their original frequencies, and means for restoring the amplitude variations of the frequency-multiplied sub-bands and combining the latter to reconstruct the original signal wave.

17. In a system for transmitting a complex signal wave comprising fundamental and harmonic frequency components, means at the transmitter for subdividing a signal wave to be transmitted into a plurality of frequency sub-bands each having a narrow band width of an order so as to substantially include not more than one of said frequency components, means for equally dividing the frequency of amplitude-limited components of each of said sub-bands, means for restoring the amplitude variations of the divided-frequency sub-bands and combining the same into a signal wave of reduced band width for transmission to a receiver, means at the receiver for again subdividing the received signal wave into its corresponding sub-bands, further means for frequency - multiplying amplitude - limited components of the received sub-bands to restore their original frequencies, means for restoring the amplitude variations of the frequency-multiplied sub-bands and combining the latter to reconstruct the original signal wave, means for subjecting said sub-bands to a frequency-substitution scrambling process before transmission, and further means for unscrambling the received sub-bands prior to reconstructing the original signal wave.

18. In a system for transmitting a complex signal wave comprising fundamental and harmonic frequency components, means at the transmitter for subdividing a signal wave to be transmitted into a plurality of frequency sub-bands each having a narrow band width of an order so as to substantially include not more than one

75

of said frequency components, means for equally dividing the frequency of amplitude-limited components of each of said sub-bands, means for producing control signals representative of the amplitude of each sub-band, means for combinedly transmitting the divided frequency sub-bands and control signals as a composite signal wave of reduced band width, means for again subdividing the received signal wave into its corresponding sub-bands, frequency-multiplying the received sub-bands to restore their original signal frequencies, further means to restore the amplitudes of the multiplied sub-bands in accordance with their respective control signals, and means for combining the resultant sub-bands to reconstruct the original signal wave.

19. In a system for transmitting speech signals, means at the transmitter for subdividing a speech signal wave to be transmitted into a plurality of frequency sub-bands each having a band width of an order of 100 cycles per second, means for equally dividing the frequency of amplitude-limited components of each of said sub-bands, means for producing control signals representative of the amplitude of each sub-band, means for combinedly transmitting the divided frequency sub-bands and control signals as a composite signal wave of reduced band width, means for again subdividing the received signal wave into its corresponding sub-bands, means for frequency-multiplying the received sub-bands to restore their original signal frequencies, further means for restoring the amplitudes of the multiplied sub-bands in accordance with their respective control signals, and means for combining the resultant sub-bands to reconstruct the original signal wave.

20. In a system for transmitting speech signals, means at the transmitter for subdividing a speech signal wave to be transmitted into a plurality of frequency sub-bands each having a band width of an order of 100 cycles per second, means for equally dividing the frequency of amplitude-limited components of each of said sub-bands, means for producing control signals representative of the amplitude of each sub-band, means for combinedly transmitting the divided frequency sub-bands and control signals as a composite signal wave of reduced band width, means for again subdividing the received signal wave into its corresponding sub-bands, means for frequency-multiplying the received sub-bands to restore their original signal frequencies, further means for restoring the amplitudes of the multiplied sub-bands in accordance with their respective control signals, and means for combining the resultant sub-bands to reconstruct the original signal wave.

21. In a system for transmitting speech signals, means at the transmitter for subdividing a speech signal wave to be transmitted into a plurality of frequency sub-bands each having a band width of an order of 100 cycles per second, means for equally dividing the frequency of amplitude-limited components of each of said sub-bands, means for producing control signals representative of the amplitude of each sub-band, means for combinedly transmitting the divided frequency sub-bands and control signals as a composite signal wave of reduced band width, means for again subdividing the received signal wave into its corresponding sub-bands, means for frequency-multiplying the received sub-bands to restore their original signal frequencies, further means for restoring the amplitudes of the multiplied sub-bands in accordance with their respective control signals, means for combining the resultant sub-bands to reconstruct the original signal wave, means for subjecting both the frequency sub-bands and control signals to a substitution scrambling process at the transmitter, and further means for unscrambling the received sub-bands and control signals at the receiver prior to the reconstruction of the original signal wave.
